UNITED STATES PATENT OFFICE.

EDWIN CHESTERMAN, OF PHILADELPHIA, PENNSYLVANIA.

FARE-REGISTER.

SPECIFICATION forming part of Letters Patent No. 226,975, dated April 27, 1880.

Application filed February 5, 1880.

To all whom it may concern:

Be it known that I, EDWIN CHESTERMAN, of Philadelphia, Pennsylvania, have invented certain Improvements in Fare Registers and Classifiers, of which the following is a specification.

The improvements relate to that class of registers known as "duplex," in which an alarm is registered on a continuous or general register, and also on a set-back or trip-register. It also has an indicator to show when or the number of times the trip-register is started on a new count.

The invention consists in the combination of devices to prevent the actuation of the handle until a pawl is raised by a cam on the raising of the bell-hammer and prevent the return of the handle until another pawl is raised by another cam on the falling of the base-hammer; also, in the combination of two ratchet-wheels on one arbor and a pawl carried by one ratchet-wheel, which pawl, by means of a pin or roller, turns the other ratchet-wheel one tooth for each revolution in either direction of the first ratchet-wheel; also, in the combination of two or more alarm mechanisms, a register to record the total number of alarms sounded, and two or more other or special registers to record the number of times each alarm has been sounded, and of other devices, as will be more particularly set forth in the following specification and accompanying drawings, in which—

Figure 1 is a plan with the case broken away and the dials removed. Fig. 2 is a section through line x x of Fig. 1. Fig. 3 is an enlarged plan of the mechanism of trip-register and the zero indicator or register. Fig. 4 is an enlarged plan of one of the general registers. Fig. 5 is an elevation of the same. Fig. 6 is a modification of the two-pronged lever. Figs. 7 and 8 are enlarged views of details. Fig. 9 is an enlarged section through line y y of Fig. 3. Fig. 10 shows the setting-back mechanism on line z z , Fig. 2. Fig. 11 is a front, and Fig. 12 a back, view of the register ready for use.

A represents the case of the register. It is composed of two parts, fitting the one into the other, the front part having two glazed openings, a' a'' , behind which the figures on the

dials may be seen, and a hole through which the trip-register may be set backward by the knob a^3 ; or a key may be used instead of the knob. It also has a perforated convex projection to cover the bell and allow the sound to pass. At the lower end of the case are two narrow openings, a^4 a^5 , through which the actuating-handles D^3 D^4 project. Knobs or thumb-pieces are attached to these handles.

A' is a part of the back of the case, riveted to the base-plate E, and is provided with a rabbet, a^6 , into which the lower part of the back is fitted, its other end being fastened to the base-plate—in the present case by means of screws a^7 , but in general use will be riveted or otherwise securely fastened. a^8 are ears for the strap by which the register is suspended. a^9 are posts projecting from the case. To these posts the base-plate E is firmly held by the screws e .

E is the base-plate, in which the posts, screws, &c., of the respective mechanisms are placed. It is fastened to the front part of the case by screws e . e' is an arm pivoted to the base-plate at e^2 , and carrying a spring-pawl, e^3 , to actuate the trip-register B. It is provided with a spring, e^4 , to return it to its normal position.

F is a post, on which the trip-register B is arbored. This register is composed of two ratchet-wheels, b for units, and b^6 for tens. Ratchet-wheel b has rigidly attached two cams, b^1 b^2 , and is fastened to a hub, on the upper end of which the figured unit-dial b^3 is fastened, and also the knob a^3 , outside the case. Cam b^2 has a notch, which engages with one end of two-pronged lever F^3 when the unit and when the zero of the trip-register show at opening a' . This cam also carries a reversible pawl, b^4 , the inner edge of which is fitted to engage (at the proper time) with the teeth of the tens-ratchet. The outer edge of this pawl is beveled in two directions, so that when in either direction it comes in contact with pin or roller e^5 it is pressed into a tooth of the tens-ratchet-wheel and turns it one tooth. When the other bevel of said pawl reaches the pin or roller it, (the pawl,) under the influence of its spring e^7 , is disengaged from the tens-ratchet.

The cam b^1 has a notch, which at each tenth movement of ratchet-wheel b is opposite one

end of locking-lever F^5 , (the other end of this locking-lever being engaged by the toothed wheel b^8 on the tens ratchet-wheel.)

Ratchet-wheel b^6 has rigidly attached a cam, 5 b^7 , a toothed wheel, b^8 , and a figured tens-dial, b^9 , and has its axis on the hub of the unit-wheel. Cam b^7 has a notch which engages with one end of two-pronged lever F^3 when the unit and when the zero of the trip-register 10 show at opening a' .

The locking-lever F^5 engages with toothed wheel b^8 to hold the tens-dial in position. At each tenth movement of the units-dial one end of said locking-lever passes into the notch of 15 cam b^7 on unit-ratchet, and its other end out of engagement with toothed wheel b^8 , allowing it and the tens-dial to turn one tooth under the influence of reversible pawl b^4 . When the tenth movement of units-dial is completed the 20 locking-lever has passed out of the notch on cam b^7 , and the tens-dial is firmly locked until the next tenth movement of the units-dial, in the same manner as is set forth in my Patent No. 176,426, dated April 25, 1876.

25 b^5 is a steadyng-pawl to ratchet-wheel b^7 . F^3 is a two-pronged bell-crank lever, pivoted at f^2 , and carrying a spring-pawl, f^3 , which engages with ratchet-wheel c' of detector indicator or register C. It is provided with a spring, f^4 , 30 which keeps it in contact with notched cams b^2 b^7 .

Ratchet-wheel c' is actuated by the pawl f^3 of the two-pronged lever F^3 each time the trip-register B is started by the actuating-handle on a new count after being set to zero by the 35 setting device.

The spring-pawl f^3 may be placed on the other side of pronged lever F^3 , as shown in Fig. 6, in which case the ratchet-wheel c' will be actuated by pawl f^3 when the trip-register 40 is set to zero. c^2 is a spring-detent to retain indicator C in position. The face of this indicator is marked to show when and how many times it is moved.

H is a device for setting the trip-register B 45 to zero. It consists of a knob or key, a^3 , ratchet-wheel H, pawl h, and spring h'.

D' are registers, actuated, respectively, by pawls d^3 d^4 of prime movers D³ D⁴. The figures on the dials of these registers are seen through 50 glazed openings d^1 d^2 in the back of the case, and are identical in construction and movement with those described in my Patent No. 176,426.

F' F² are bell-hammers, actuated by spring-55 pawls d^5 d^6 on the respective prime movers. They are each provided with cams f^5 f^6 , which, at the proper time, engage with the respective spring-detents f^7 f^8 . Each hammer has a tooth, f' , by which it is raised, and a spring, f^9 , the 60 retractive force of which causes it to strike the bell F⁴. A post, f, holds the hammer from resting on the bell.

G is a steel spring snapper or sounder, acted upon by tooth d^3 on the prime mover D⁴. 65 D³ is an actuating-handle, provided with slots d^9 , fitting over and working on guide-posts e^8 , projecting from the base-plate, (these posts

limit the movement of the actuator.) It is also provided with spring-paws d^3 d^5 , to actuate the register D and the long bell-hammer 70 F'. On the upper end of this actuating-handle is an arm, d^{14} , extending across to pin e^6 on the arm e' , which actuates the trip-register. On the inner edge of handle D³ are ratchet-teeth d^7 d^8 . D⁴ is also an actuating-handle, 75 provided with slots d^{12} , fitting over and working on guide-posts e^9 , projecting from the base-plate, (these posts limit the movement of the actuator.) It is also provided with spring-paws d^4 d^6 , to actuate the register D' and the 80 short bell-hammer F². On the upper end of this actuating-handle is an arm, d^{15} , extending across to a pin on the arm e' , which actuates the trip-register.

On the inner edge of handle D⁴ are ratchet-teeth d^{10} d^{11} . On the lower end of this handle is a tooth, d^{13} , by which the spring-snapper G is actuated.

f^7 f^8 f^9 f^8 are spring-detents pivoted on the base-plate. These detents are fitted to engage 90 with the ratchet-teeth in the actuating-handles to insure proper actuation of the machine.

The operation is as follows: The trip-register being at zero, to register a full fare the handle D³ is pulled, when pawl d^5 comes in 95 contact with tooth f' on bell-hammer F', and raises the hammer and presses the cam f^5 on the tail of spring-detent f^7 , raising its point away from ratchet d^7 , and allows the handle D³ to be drawn out. The cam f^6 moves out of 100 contact with tail of spring-detent f^8 and allows its point to engage with ratchet-teeth d^8 . The spring-pawl d^3 engages the first wheel of register D, turning it one tooth. The projecting arm d^{14} comes in contact with pin e^6 on arm e' , 105 pressing it down, and causes its pawl e^3 to actuate ratchet-wheel b of the trip-register, and the pronged lever F^3 is turned on its pivot by the notched cam b^2 , causing its pawl f^3 to actuate the detector-indicator C. The pull on handle D³ being continued, the pawl d^5 passes out of engagement with bell-hammer F', which, under the influence of its spring, strikes the bell F⁴. The cam f^6 strikes the tail of detent f^8 , and raises its point from ratchet d^8 , and allows the handle D³ to return to position under the influence of spring D⁵. The cam f^5 moves 110 away from detent f^7 and allows it to engage with ratchet d^7 .

At each tenth actuation of ratchet-wheel b 110 the reversible pawl b^4 , coming into contact with pin or roller e^5 , is pressed into a tooth of the ratchet-wheel b^6 and turns it, and the tens-dial advances one number.

To register a half fare the handle D⁴ is pulled 115 and the pawls register, and hammer on that side operates in the same manner as described for the full-fare register, and in addition the tooth d^{13} presses down the steel blade G, which causes a snapping sound, as described in my Patent No. 176,426, and denotes the registration of a half fare.

It will be seen that the actuation of either handle, D³ or D⁴, causes their respective pro-

jecting arms d^{14} d^{15} to actuate the trip-register, and that while the registers D D' register their respective alarms the register B registers the total alarms of both registers for each trip.

5 The trip being finished, it is desired to set the trip-register to zero without interfering with the general registers and alarms. This is accomplished by turning the knob or key a^3 to the right. This carries the unit-dial b^3 backward until the reversible pawl b^4 comes in contact with pin or roller e^5 , when it is pressed into a tooth of ratchet-wheel b^6 and turns it, and the tens-dial recedes one number. This is continued until the unit shows at opening 10 a' , when the two-pronged lever F^3 registers with notched cams b^2 b^7 , and is turned back until the zero shows at opening a' , when the pawl f^3 will be ready to engage with the ratchet of the detector-indicator when either handle is 15 actuated, as shown in Fig. 1; or, if the pawl f^3 is placed as shown in Fig. 6, the detector-indicator is actuated when the trip-register is turned back to zero, instead of when started on a new count.

25 Two series of ratchet-teeth and a reversible pawl to insure a full reciprocation is not new. It is set forth in Patent No. 45,868, January 10, 1865.

Different kind of alarms to denote different 30 class of fares is not new. It is set forth in my Patent No. 176,426, April 25, 1876.

I claim as of my invention—

1. The combination of register D, actuating-handle D^3 , ratchet d^7 , spring-detent f^7 , hammer F' , spring f^9 , and cam f^5 , substantially as and for the purpose set forth.

2. The combination of register D, actuating-handle D^3 , ratchet d^8 , spring-detent f^8 , hammer F' , spring f^9 , and cam f^6 , substantially as 40 and for the purpose set forth.

3. The combination of register D, actuating-handle D^3 , ratchets d^7 d^8 , spring-detents f^7 f^8 , hammer F' , spring f^9 , and cams f^5 f^6 , substantially as and for the purpose set forth.

45 4. The combination of a pin or roller with the ratchet-wheels of a register and their common arbor and a reversible pawl carried by the first ratchet-wheel to turn the second ratchet-wheel one tooth for each revolution in either 50 direction of the first ratchet-wheel, substantially as set forth.

5. The combination of actuating-pawl e^3 , arbor F, ratchet-wheel b, reversible carrying-pawl b^4 , pin or roller e^5 , ratchet-wheel b^6 , and 55 setting device H, substantially as set forth.

6. The combination of two or more alarm mechanisms, a register to indicate the number of times either of said alarms has been sounded, and two or more special registers to record how many times each alarm has been 60 sounded, substantially as set forth.

7. The combination of two or more alarms, the different sound or kind of which designates a different class or value, a register to indicate how many times either of said alarms 65 has been sounded, and two or more special registers to record how many times each of the different alarms has been sounded, substantially as set forth.

8. The combination of arm e' , pawl e^3 , register B, actuating-handles D^3 D^4 , pawls d^3 d^4 d^5 d^6 , bell-hammers F' F^2 , and registers D D', substantially as set forth.

9. The combination of arm e' , pawl e^3 , register B, actuating-handles D^3 D^4 , pawls d^3 d^4 75 d^5 , tooth d^{13} , bell-hammer F' , bell F^4 , click or sounder G, and registers D D', substantially as set forth.

10. The combination of a trip or set-back registering mechanism, consisting of two or 80 more ratchet-wheels, constructed substantially as described, and a general or continuous registering mechanism independent of each other, an alarm, an actuating-handle common to all three, a device for setting the trip-registering 85 mechanism back to zero-point independent of the alarm and general register, and a zero indicator or register, and intermediate mechanism operated by the actuating-handle to show when or how many times the trip-registering 90 mechanism is started from zero after being set back thereto by the setting device, substantially as set forth.

11. The combination of two or more independent alarm-registers and their actuating 95 mechanisms, independent of each other, with the actuating mechanism of a trip or set-back register, consisting of two or more ratchet-wheels constructed substantially as described, a device for setting the trip-register to zero 100 independent of the alarm-registers, and a zero indicator or register to show when or how many times the trip-register is set back to or started from zero after being set back thereto by the setting device, substantially as set forth. 105

EDWIN CHESTERMAN.
